CLAIM

The ornamental design for a box with weave design, as shown and described.

DESCRIPTION

FIG. 1 is a photograph of a perspective view of a box with weave design showing the new design;

FIG. 2 is a photograph of a left side view thereof;

FIG. 3 is a photograph of a right side view thereof;

FIG. 4 is a photograph of a front view thereof;

FIG. 5 is a photograph of a back view thereof;

FIG. 6 is a photograph of a top view thereof;

FIG. 7 is a photograph of a bottom view thereof;

FIG. 8 is a photograph of a perspective view of the box with weave design in an open configuration with a portion of the box removed;

FIG. 9 is a photograph of a front view thereof;

FIG. 10 is a photograph of a left side view thereof;

FIG. 11 is a photograph of a right side view thereof;

FIG. 12 is a photograph of a back view thereof;

FIG. 13 is a photograph of a top view thereof;

FIG. 14 is a photograph of a bottom view thereof; and,

FIG. 15 is a photograph of a perspective view of the box with weave design of FIG. 8 showing exemplary products displayed in the box.

The portion in FIG. 15 shown in course dot pattern and outlined in dashed lines form no part of the claim.

1 Claim, 13 Drawing Sheets
